A. F. JACKSON.

BACK OF BRUSHES, MIRRORS, &c.

o. 20,433.

Patented Dec. 23, 1890.

UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR BACK OF BRUSHES, MIRRORS, &c.

SPECIFICATION forming part of Design No. 20,433, dated December 23, 1890.

Application filed November 17, 1890. Serial No. 371,749. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Backs of Brushes, Mirrors, &c., of which the following is a specification, reference being had to the accompanying illustration, forming part thereof.

10 The figure is a photographic illustration of the back of a hair-brush or hand-mirror.

My design for the backs of hair-brushes, hand-mirrors, &c., is of a paddle shape, the outline being wrought into reversed curves 15 arranged symmetrically upon opposite sides of a middle longitudinal line. A marginal border *a* of inwardly-turned scrolls is arranged around the back proper, and within this is another border *b* of scrolls, forming a central

panel *c*. Between the two borders *a* and *b* are arranged sprays of flowers *d*. The handle 20 in outline has a reduced neck *f* and swelled portion *e* and bears a symmetrical and harmonious ornamentation of scrolls *f' f''* and flowers *g*.

The leading features of my design are the double borders *a b* of scrolls, with the sprays 25 of flowers *d* between the same, the handle portion of the brush-back being subordinate and non-essential.

What I claim is—

The design for the backs of brushes, hand-mirrors, &c., as herein shown and described.

AUSTIN F. JACKSON.
